TENSION PRESS FOR SHEET MATERIALS

John H. Pearce, Seattle, Wash.

Application June 10, 1949, Serial No. 88,215

2 Claims. (Cl. 100—269)

1

My present invention relates to presses of the type that are designed for use in the formation of sheet materials, particularly those used in the building trades, such as plywood, the various fibrous boards that are normally formed under compression and combinations of wood or wood products and paper or plastic. My press is characterized by an arrangement which permits the application of very high pressures but which places the structural elements of the press largely in tension. In this way, large castings and the like are avoided and steel rod stock that is most suitable for sustaining large tension loads, can be used to advantage.

Generally my press consists of a reenforced concrete base in which are employed a plurality of cylinders, each equipped with a piston rod which extends upwardly and are individually joined to an upper or strong back section. Consequently, when the press is under use, the chief items in strain are the relatively large piston rods which exert the pressure and these are in tension.

In the past it has been most common to use normally a single hydraulic piston of large size and to have a heavy cast metal base platen which was raised and lowered by this piston. This requires that a very heavy upper framework be employed and this normally results in heavy castings, which are both expensive in first cost and whose transportation to the site of use is a major problem; and then again, normally, cast metal can never obtain the strength per unit of cross sectional area that can be found in alloy steel rod stock.

In my present press arrangement, I believe I have overcome many of the deficiencies noted in the past and provide a unit that can be largely fabricated on the job from such common items as cement and concrete aggregate, reenforcing steel and cylinders, pistons, valves, screw jacks and the like, which are stock items easily obtained in most any locality. Such an arrangement allows great flexibility in design and is capable of producing a tension press which is quick in operation, light and flexible in use, and can be built in any size or for any pressure requirement. This all can be achieved through the use of equipment which results in a finished product that is simple and inexpensive.

The principal object of my present invention, therefore, is to provide a tension press in which the piston rods of a plurality of hydraulic cylinders are employed to support, move and apply the necessary force to an upper block to bring it down into compressive co-action with a substantial base member.

2

5 A further object of my present invention is to provide a tension press in which instead of building a large concrete base upon which to mount a press, the press uses concrete as an integral part of the press, and therefore, the lower element of the press in effect forms its own foundation and does not need to be secured in place.

10 A further object of my press is to provide a "cast in place" lower base section and an upper or strong back tension member, which may be drawn toward each other by means of tension rods acting in unison, due to the fact that all the various cylinders are piped together and have a common source of pressure fluid.

15 A further object of my invention is to provide a tension press in which all the various working elements are easily replaceable, and while this creates a device that has low initial cost, future replacement costs or servicing is reduced to a very economical operation.

20 Further objects, advantages and capabilities will be apparent from the description and disclosure in the drawings, or may be comprehended or are inherent in the device.

25 In the drawings:

Figure 1 is a side elevation of a press for sheet materials made after the teachings of my present invention;

Figure 2 is an end elevation of my press shown in Figure 1, with certain parts broken away to better illustrate the construction;

Figure 3 is a top plane view of my press, with certain parts broken away at different elevations, in order to more clearly illustrate the construction;

35 Figure 4 is a vertical sectional view of a typical cylinder assembly employed in my equipment, the same being shown as broken away in order to increase the size of the essential parts;

40 Figure 5 is a cross sectional view taken along the line 5—5 of Figure 4; and

Figure 6 is a schematic diagram illustrating the fluid pressure arrangement of my press.

45 Referring more particularly to the disclosure in the drawings, the numeral 10 designates one of the hydraulic cylinders used in my device. The number of these units will be determined by the pressures required and the area to be subjected to the pressure. Throughout my drawings I have shown a unit composed of eight such cylinders. Each cylinder is set in a niche provided in the base member 12; extending upwardly from cylinder 10, is the piston rod 14. These are driven upwardly or downwardly by the double-
50 acting piston 16. Disposed vertically above base 12, is the upper or "strong back" section 18.

Forming the main element of the strong back is a plurality of channels, as 20 and 22. These are arranged in pairs back to back, with holding nut 24, and lock nut 25, on the upper side of the strong back, so as to accept the full strain of compression when the press is working. On the under side of the strong back, a positioning nut 26, is employed. In order to assist in providing a true flat plane which will not bend under pressure between the various supports, I provide a platen plate 28, which is spaced away from channels 20 and 22 by a plurality of I beams, 30. This construction is probably best illustrated in Figures 1, 2 and 3. Similarly, to provide a true plane surface, I use a lower platen plate, 32, on top of the member 12.

A section through a typical cylinder assembly is shown in considerable detail in Figures 4 and 5. These units consist of the sleeve or cylinder proper 34, in which piston 16 is disposed for reciprocation. The lower end of the cylinder is preferably solid and relieved as at 36 as a matching convenience, so that piston 16 partially overruns the cylinder wall proper, and thus any wear will be uniform throughout the whole length of the cylinder. At its upper end, the cylinder is provided with a cylinder head, 38, having the stuffing box arrangement shown at 40, through which piston rod 14 passes. The type of packing surrounding rod 14 will have to be balanced against the maximum pressure to be retained. For extreme pressures, the so-called metallic ring packing has been found most practical. Cylinder head 38 has a sealing ring, usually of deformable metal, as 42, to insure a seal under working pressures. The cylinder head is held in place by virtue of the two part housing member 44. This member is formed in two parts, so that it can conveniently engage the cylinder and the cylinder head, after the showing of Figures 4 and 5.

It will be noted that the cylinder proper has a seat at 46, which has a sloping surface, as 47. Similarly, the cylinder head has a similar sloping surface, as 48. Housing 44 is machined to accommodate these bevels and when the unit is put in place and bolts 50 and 51 set up tight, ring 42 is compressed and a secure, leak-proof head is provided for the cylinder. A fluid line, 53, enters through the head. Similarly, at the lower end of the cylinder, another fluid line, 55, is employed. These serve either as pressure supply lines or exhaust lines in accordance with the valve settings and the direction of movement of the piston.

It will be noted from Figures 1, 2 and 3 that each of the cylinders 10, seat in niches, which are U-shaped. These niches are shown in Figure 3, in plan, at 56. A very narrow U-shaped slot is provided in the heavy ledge of concrete above the piston, as at 58, so that piston rod 14 may pass therethrough and still leave adequate strength in the material of portion 58. A very complete steel reinforcement should be employed in this concrete base and the same should be relatively rich in cement. In Figures 1 and 2, the reinforcing steel is shown in dotted lines at 60 and 61. The same is also shown in full lines in Figure 3. To serve certain conditions where very high pressures are needed or where weight is a prime consideration, a base fabricated of structural steel members, after the teachings of the top or "strong back" member construction, may be employed.

It will be noted from Figure 4 that a heavy

top plate is provided for housing 44, as the plate 63. The plate in turn abuts under the ledge formed by portion 58 and niche 56, and secure engagement is provided by means of the screw jack 65, there being one jack for each cylinder. As it is desirable that these cylinders be easily replaceable, this is a convenience in the initial construction of the machine and in varying the machine for different loads, entirely aside from the ease with which they can be removed if servicing is required.

In Figure 6 I have shown in diagrammatic form, the hydraulic pressure system which has proved to be satisfactory as a means for producing the high pressures required in a press of this order, if, for instance, plywood is to be bonded. This requires a unit pressure of approximately 15 pounds per square inch over a sheet normally 4 x 8 feet in extent and the pressure required is tremendous. To achieve this, I use, normally, a water pump, 70, which will produce reasonable pressure. It should be usually of the non-pulsating type, such as the multi-gear type pump or a centrifugal pump of either single or two stage arrangement. This I drive by any suitable power, as by the electric motor 72. Water is used in a closed circuit involving the water reservoir 74, and by means of the four-way valve shown at 75, a water circuit through the pipes or tubes 77 and 78, is provided, which acts upon the double-acting piston 80 within cylinder 82. In this arrangement, tubes 77 and 78 may be either supply or discharge in accordance with the movement of piston 80.

Piston 80 is directly connected to a high pressure piston 84, which has but a fraction of the area of piston 80. Piston 84 operates in the double-acting cylinder 85 and consequently again, the high pressure pipes 87 and 88, may be either supply or discharge, in accordance with the setting of valve 90. In this I prefer to use a closed oil circuit with a reserve reservoir 92. There are a number of commercial oils that serve this purpose, although for certain uses, a mixture of water, alcohol and a small amount of sperm oil, proves very satisfactory. This, following the proportions used in recoil cylinders of cannon, hydraulic jacks and the like. In accordance with the setting of valve 94, which is again a four-way valve, the high pressure fluid is forced through either tube 53 or 55, these being led respectively to the upper portion of cylinder 10 and to the lower portion of the same. It will be noted from Figure 6 that the cylinder units are piped in parallel, so that the same pressure will be present in each cylinder. This is particularly true in the manner in which these machines are used, as considerable time is available to build up and distribute the pressure. When so arranged, it will be apparent, it is believed, that each of the various piston rods, 14, will have the same force applied to it, whether directed to raise the piston rod or retract it, as occurs in the pressing operation. Now it has been found that with a substantial base as indicated in the drawings by reference character 12, and by means of the platen plates 28 and 32, that very uniform pressure can be applied to relatively large sheet materials. Further, the system is a very workable one, in that by having a control handle on valve 94, a nicety of movement can be effected to either raise the upper pressure member or "strong back" 18, or to bring it down upon a stack of sheet stock for the pressing operation.

It is believed that it will be clearly apparent

from the above description and the disclosure in the drawings that the invention comprehends a novel construction of a tension press for sheet materials.

Having thus disclosed the invention, I claim:

1. A tension press for sheet materials, consisting of: a lower base section; an upper press strong back; a plurality of double-acting press cylinders removably secured in a vertical arrangement within niches in said lower base section; double-acting press pistons disposed for reciprocation in said cylinders; piston rods operatively connecting said pistons and said upper press strong back; said lower base section being formed of re-enforced concrete having a ledge portion disposed above each cylinder; jacks adapted to seat the upper portion of each cylinder firmly against said ledge portion; said upper press strong back being fabricated from structural steel shapes.

2. A tension press for sheet materials, consisting of: a fabricated lower base section; a fabricated upper press section; a plurality of double-acting press cylinders secured in a vertical arrangement within opposite sides of said lower base section; double-acting press pistons reciprocatively disposed in said cylinder; piston rods operatively connecting said pistons and said upper press section; said cylinders having a flange at their upper ends with a beveled lower

5

10

surface; a piston head having a peripheral extension with a beveled upper surface; a clamp, split vertically and having an annular groove adapted to engage the beveled surfaces of said cylinder and said piston head and hold said head securely to said cylinder; a high pressure hydraulic system to provide fluid to said cylinders; tubing adapted to lead high pressure fluid from said high pressure system to each end of said press cylinders; and valve means adapted to selectively control the direction of fluid flow to said press cylinders.
